UNITED STATES PATENT OFFICE.

WILLIAM C. WEICHSEL, OF WHEELING, WEST VIRGINIA, ASSIGNOR TO AMERICAN SHEET AND TIN PLATE COMPANY, OF PITTSBURGH, PENNSYLVANIA, A CORPORATION OF NEW JERSEY.

PACKAGE.

Application filed October 27, 1927. Serial No. 229,182.

This invention relates to packages for plates and, while not limited thereto, relates more particularly to shipping skids and packages for light gage plates, such as tin plate, 5 and has for its object the provision of a light, durable and cheap skid and package which is particularly adapted for mechanical loading and handling.

In the drawings—

10 Figure 1 is a top plan, partly broken away, of a package of tin plate formed on the skid of this invention.

Figure 2 is a side elevation thereof.

15 Figure 3 is an end elevation thereof.

Figures 4 and 5 are detail views of the tie-wire supporting clips.

20 Referring more particularly to the drawings, the numeral 2 designates the rectangular supporting members which are preferably formed of standard wood sections. The supporting members 2 are all of the same cross-section and length and are spaced substantially an equal distance apart.

25 Angle-shaped side members 3 are secured to the upper or top faces of the supporting members, adjacent their ends. The angle-shaped side members are arranged with one flange parallel with the top faces of the supporting members 2 and with their other flange 0 projecting upwardly at right angles to the top face of the supporting members, so as to prevent the plates piled on the skid from moving sidewise off of the skid. The side members 3 are preferably secured to the supporting members by nails, screws or the like, 5 as at 4, so as to form a rigid unit or skid.

In practice, skids formed as above described are arranged on the floor and the plates 5 are piled thereon until the desired number are assembled. Experience has shown that eleven base boxes or one thousand one hundred and twenty plates may be readily piled on a single skid.

After the plates are piled on a skid, angle-shaped clips 6 are mounted along the upper side edges of the pile of plates with one flange overlying the top face of the pile and the other flange overlying the side face of the pile. The clips 6 are provided with spaced upstanding ribs 7 for a purpose to be described.

The clips 6 are located in line with the spaces between the supporting members 2 and tie wires 8 are passed over the pile of plates

5 and clips 6, so as to extend between the ribs 55 7 on the clips, and then under the angle side members 3 and pile of plates, and have their ends secured together, as at 9, so as to bind the pile of plates and the skid together, forming a suitable package for shipping. The 60 clips 6 prevent the tie wires from damaging the plates and the ribs 7 prevent the tie wires from slipping off of the clips.

After the plates and skid have been tied together, forming a completed package, the 65 entire package is adapted to be handled mechanically by a lift tractor or other device having a forked or pronged lifting member which may be inserted under the package between the supporting members 2 to lift the 70 package clear of the floor.

While I have shown and described one specific embodiment of my invention it will be understood that I do not wish to be limited thereto since various modifications may be 75 made without departing from the scope of my invention as defined in the appended claim.

I claim—

80 A package of tin plate or the like comprising a base composed of a plurality of spaced supporting members arranged in parallel relation with each other, angle members extending along the upper faces of all of said supporting members adjacent each end thereof, said angle members being arranged with one flange parallel with the upper faces of said supporting members and with the other flange extending upwardly at right angles to the top faces of said supporting members, 85 said angle members and said supporting members being rigidly secured together, a pile of plates supported on said supporting members and angles, angle-shaped clips mounted in spaced relation along the upper 90 side edges of said pile of plates so as to have one flange overlying the top face of said plates and the other flange overlying the side face of said pile of plates, tie wires extending over said pile of plates and said angle-shaped clips and under said base to secure said base and pile of plates together, and ribs on said clips to prevent said wires slipping off of said clips.

100 In testimony whereof, I have hereunto set 105 my hand.

WILLIAM C. WEICHSEL:
